UNITED STATES PATENT OFFICE.

JAMES I. AYER, OF MALDEN, MASSACHUSETTS, ASSIGNOR TO THE SIMPLEX ELECTRICAL COMPANY, OF BOSTON, MASSACHUSETTS, A CORPORATION OF MASSACHUSETTS.

OPERATING MECHANISM FOR MOTOR-RHEOSTATS.

SPECIFICATION forming part of Letters Patent No. 700,715, dated May 20, 1902.

Application filed February 17, 1902. Serial No. 94,351. (No model.)

To all whom it may concern:

Be it known that I, JAMES I. AYER, a citizen of the United States, residing at Malden, county of Middlesex, State of Massachusetts, 5 have invented an Improvement in Operating Mechanism for Motor-Rheostats, of which the following description, in connection with the accompanying drawings, is a specification, like letters on the drawings representing like parts.

My invention is an operating mechanism for motor-rheostats, and has for its object the provision of special means for insuring that the armature resistance of a rheostat shall be 15 cut out before the field resistance of the rheostat is cut in, or, in other words, that the armature-control arm shall be shifted before the field-control arm is shifted in starting and controlling a motor. Preferably, also, in 20 connection therewith I provide means for insuring that the field resistance is cut out before the armature resistance has been cut out in starting or stopping the motor. Also 25 the more complete embodiment of my invention preferably includes the mounting of the field-control arm and the armature-control arm together, so that they are mutually dependent.

The constructional details and further advantages of my invention will be more fully 30 pointed out in the course of the following description, reference being had to the accompanying drawings, in which I have illustrated preferred embodiments thereof, and the invention will be more particularly defined in 35 the appended claims.

In the drawings, Figures 1 and 3 show different forms of my invention in front elevation. Figs. 2 and 4 are diagrammatic views 40 thereof, illustrating the wiring; and Fig. 5 is a side elevation of portions of Fig. 3.

On a suitable insulating-base a is mounted a usual rheostat-head, consisting of usual contacts a' and contact-bar b , the former being connected by resistances a^2 and at its right-hand end, as herein shown, being connected by a wire a^3 to the armature a^4 and thence by wire a^5 to one of the line-wires a^6 and the latter being connected by a wire a^7 to the 50 shunt-field a^8 , which is connected to the line-

wire a^6 , an electromagnet a^9 being interposed in said wire a^7 for electrically retaining the armature a^{10} of a magnet-arm a^{12} , yieldingly mounted on the same stud a^{13} as the armature-control arm a^{14} .

The two arms a^{12} a^{14} are normally held under tension when in the position shown in Fig. 3 by means of springs s s' , attached at one end to said arms, respectively, and at the other end secured by suitable means, as 60 in a slot s^2 , to the hub when the device is used as a motor-starting rheostat only; but when used for motor-controlling rheostat the arm a^{12} is alone held under the control of a spring s .

The mechanism thus far described is such 65 as is commonly employed and may be widely varied so far as concerns my invention, the purpose of said mechanism being to provide means for insuring that when the field-circuit is interrupted or when an overload occurs the arm a^{14} will be automatically shifted to its "off" position by the release of the arm a^{12} , which during proper operation is retained magnetically by the electromagnet a^9 , and the further purpose of my invention being to provide in connection therewith means 75 dependent thereon for controlling the field resistance.

Referring first to Figs. 1 and 2, which show my invention in its simpler form for light 80 work, it will be seen that I have mounted at b' on the arm a^{14} a field-control arm b^2 , provided with an operating-handle b^3 for swinging its free end into successive engagement with field-resistance contacts b^4 , whose resistances connect with the contact-bar b of the shunt field-circuit, and, as herein shown, the circuit is completed from the line-wire a^{15} by the arm a^{14} and the arm b^2 , which are 85 themselves conductors or provided with conductors.

In operation it will be evident that when current ceases in the field or other disturbance arises which renders the electromagnet a^9 inoperative the arm a^{12} will instantly be 95 thrown over to the left by its spring s first striking the arm b^2 , and thereby shifting the latter to the left, cutting out the field resistance, and then shifting both of the arms b^2 and a^{14} over to the off position or contact 100

- a^{16} . When in this position, it is impossible to introduce the field resistance, because the motion of the arm b^2 is limited, in the first place, by a stop or other means b^5 , and, in the next place, it is so mounted and of such length that it is impossible for it to make contact with the resistance-contacts b^4 until the armature-control arm has been shifted to the extreme right.
- 10 It will be understood that the mechanism just described is merely one form or embodiment of my invention, although because of its simplicity it is a desirable form. In Figs. 3 to 5, however, I have shown another embodiment of my invention, which for heavy work has its advantages over the mechanism just explained. Referring to said figures, it will be seen that I have not used the arms as conductors, but have provided a contact-bar b^6 , connected by a wire b^7 to the line conductor a^{15} , and a contact-bar a^{17} , connected by a wire a^{18} also to said line-wire.
- 15 It will be understood that I have omitted various constructional details which are commonly found in devices of this general nature and have confined myself as much as possible to those features necessary to the clear description and understanding of my invention.
- 20 The field-control arm is indicated at b^8 and is preferably pivoted on the stud a^{13} , swinging freely independently of the two arms a^{12} a^{14} , which, as already described, are both spring-controlled when used solely as a starting-rheostat, in which case the arm a^{14} is also provided with locking means, herein shown as comprising a notched plate a^{19} and a latch or dog a^{20} , mounted in ears a^{21} on the base a and normally held downward by a spring a^{22} .
- 25 The arm b^8 is locked in engagement with the arm a^{14} at all times, excepting when the latter is in its extreme right position, when it is automatically unlocked, any convenient form of mechanism being employed, that
- 30 herein shown comprising a pin a^{23} , vertically movable in the arm a^{14} and normally held downward by a spring a^{24} , said pin carrying at its upper end an arm a^{25} , provided at its free end with a detent a^{26} to engage a hole or notch a^{27} in the arm b^8 , being released therefrom by engagement with an inclined plate a^{29} , mounted on the base a in position to release said parts only when the arm a^{14} has reached the last contact a' at the right.
- 35 The locking device a^{20} of the armature-control arm a^{14} extends into the path of the magnet-arm a^{12} , so that when the latter flies upwardly it first shifts the arm b^8 to the left, so as to remove it from the field-resistance contacts, and in passing it releases the locking device a^{20} from the notched plate a^{19} of the arm a^{14} , thereby permitting all three arms to move instantly to the left into off position, the arm b^8 being meanwhile locked against the arm a^{14} by the locking mechanism carried thereby. Upon desiring to start up the motor again the operator first moves the lever

a^{12} to the right into contact with the electromagnet a^9 and then moves the arm a^{14} to the right, holding the arm a^{12} in position until the arm a^{14} reaches the first contact a' , after which the arm a^{12} is held magnetically by the current passing through the magnet-circuit. When the arm a^{14} has been moved to the extreme right, the arm b^8 (in the construction shown in Fig. 1) or the arm b^8 (in the construction shown in Fig. 3) can be at once shifted over the field-resistance contacts as may be desired, the arm a^{14} in the construction shown in Fig. 3 being locked in its right-hand position automatically by the dog a^{20} and the arm b^8 simultaneously unlocked by the pin a^{23} and plate a^{29} .

In both forms of my invention it will be seen that mechanism is provided which makes it impossible to introduce field resistance into the shunt field-circuit excepting when the motor has been properly controlled or started by the cutting out of armature resistance.

As herein shown, the field-control mechanism cannot be made operative until the armature-control mechanism has arrived at its "short-circuit" position, (as it is commonly termed when the external resistance has been cut out of the circuit.)

As already intimated, I do not limit my invention to the constructional details herein shown and explained, as the invention in its broader aspects is capable of a variety of embodiments, and accordingly I do not intend to limit this invention otherwise than as herein-after expressed in the claims.

Having described my invention, what I claim as new, and desire to secure by Letters Patent, is—

1. In a device of the kind described, armature-control mechanism, field-control mechanism, means for locking said armature-control mechanism in short-circuit position, and means preventing the operation of said field-control mechanism until the armature-control mechanism has arrived at said short-circuit position.

2. In a device of the kind described, a rheostat, comprising a field-control lever and resistances therefor, an armature-control lever and resistances thereof, and means for positively moving the field-lever back to neutral position when the armature-lever is moved back to neutral position.

3. In a device of the kind described, armature-control mechanism, field-control mechanism, the latter requiring movement independent of the former for placing it in operative position, and a locking device for locking the said two mechanisms together until the armature-control mechanism has been moved to short-circuit position.

4. In a device of the kind described, armature-control mechanism, field-control mechanism, the latter requiring movement independent of the former for placing it in operative position, a locking device for locking said two mechanisms together until the armature-

control mechanism has been moved to short-circuit position, and means for then automatically unlocking said two mechanisms to permit said independent movement of said field-control mechanism.

5. In a device of the kind described, armature-control mechanism, field-control mechanism, means for locking said armature-control mechanism in short-circuit position, said field-control mechanism being operable independently of said armature-control mechanism when the latter is locked, and means controlled by the motor-circuit for automatically shifting said field-control mechanism and unlocking said lock upon interruption of said motor-circuit.

6. In a device of the kind described, field-control mechanism including a lever and a series of resistances, armature-control mechanism including a lever and a series of resistances, and means under the electrical control of the motor-circuit for automatically shifting said field-lever to cut out the field resistances before movement of the armature-lever.

7. In a device of the kind described, field-control mechanism including a lever and a series of resistances, armature-control mechanism including a lever and a series of resistances, means under the electrical control of the motor-circuit for automatically shifting said field-lever to cut out the field resistances before the movement of the armature-lever, and means coöperating therewith for withdrawing the field-lever and putting it into inoperative condition until the armature-lever has been put in short-circuit position for again starting the motor.

8. In a device of the kind described, a rheostat including field resistances, armature resistances, and independently-movable levers therefor, means for locking said two levers together excepting when the armature-lever is in its short-circuit position, and means for automatically unlocking said levers when the armature-lever is moved to its short-circuit position.

9. In a device of the kind described, an armature-control lever, resistances therefor, a spring-actuated device held under tension by the passage of current in the motor-circuit, a field-control lever, and resistances therefor included in a shunt field-winding, said field-control lever being located between said armature-control lever and said spring device, interruption of the retaining current of said spring-actuated device permitting the latter to shift said field-control lever for cutting out the field resistance before movement of the armature-control lever.

10. In a device of the kind described, resistance in a shunt field-winding, armature resistances, independent levers therefor coaxially mounted, and automatic means for shifting said levers, said shifting means engaging and shifting the field-control lever for cutting out its resistances, before engaging and operating the armature-control lever.

In testimony whereof I have signed my name to this specification in the presence of two subscribing witnesses.

JAS. I. AYER.
